UNITED STATES PATENT OFFICE.

SETH WILLIAM BABBITT, OF MERIDEN, CONNECTICUT, ASSIGNOR TO THE INTERNATIONAL SILVER COMPANY, OF SAME PLACE.

DESIGN FOR A RECEPTACLE.

SPECIFICATION forming part of Design No. 35,140, dated October 1, 1901.

Application filed August 15, 1901. Serial No. 72,194. Term of patent 7 years.

To all whom it may concern:

Be it known that I, SETH WILLIAM BABBITT, a citizen of the United States, residing at Meriden, in the county of New Haven and State of Connecticut, have invented and produced a new and original Design for a Receptacle; and I do hereby declare the following to be a full, clear, and exact description of the same, reference being had to the accompanying drawing, forming a part thereof.

This invention relates to a new and original design for a receptacle, and it is embodied in the general arrangement, configuration, and shape of a receptacle presently to be described, and shown in the accompanying drawing.

In the drawing the design is illustrated in elevation.

The base portion of the receptacle A consists of two portions of substantially similar formation, but varying in size and diameter and separated by an intervening bulged portion. Surmounting the base is a body portion B, the lower part of which is curved outwardly and has on its face suitable fanciful ribs b. The upper portion of the body is curved inwardly and thence outwardly at its upper edge and has formed thereon fanciful

beads or ribs b', forming continuations of the ribs b. Directly below the upper edge of the receptacle the fanciful ribs b' are branched to constitute fanciful sprays or scrolls, meeting at the center. A suitable pinnated cluster is located at the base of the inclined portion of the body part B.

The essential feature of the design is the shape and general decorative feature of the body portion.

It may be stated that the receptacle forming the subject-matter of this design is intended mainly as a receptacle for a candle and is to be placed on a candelabra or candlestick, yet it is to be understood that the same may be applied to other articles.

Having thus described the invention, what is claimed as new, and desired to be secured by Letters Patent, is—

The design for a receptacle substantially as shown and described.

In testimony whereof I affix my signature in presence of two witnesses.

SETH WILLIAM BABBITT.
